UNITED STATES PATENT OFFICE.

ROBERT G. LOWE, OF CLAWSON, MICHIGAN.

SAND-SIFTER.

1,354,319.

Specification of Letters Patent. Patented Sept. 28, 1920.

Application filed June 17, 1920. Serial No. 389,602.

To all whom it may concern:

Be it known that I, ROBERT G. LOWE, a citizen of the United States, and residing at Clawson, in the county of Oakland and 5 State of Michigan, have invented a new and Improved Sand-Sifter, of which the following is a specification.

This invention relates to means for shaking and agitating sieves and screens and 10 other containers for foundry and builders' sand and other granular substances, and for liquids, and its object is to provide a device of this character which is readily transportable as a unit, which shall have maximum 15 capacity, which shall be simple in construction and which shall not be liable to get out of order.

This invention consists in the combination 20 of an electric motor comprising the usual armature and its shaft and a field housing of any desired type, of a casing in which the motor housing is rigidly mounted with the armature shaft in upright position, of an eccentric at the upper end of the armature 25 shaft, a supporting frame for the casing, and a container such as a screen, sieve or riddle resiliently mounted on said supporting frame and means connecting the container to the eccentric on the shaft so that 30 the container will receive a gyratory movement from said eccentric.

It also consists in the details of construction illustrated in the accompanying drawings and particularly pointed out in the 35 claims.

In the accompanying drawings, Figure 1 is an elevation of a sand sifter embodying my improvements. Fig. 2 is a plan on the line 2-2 of Fig. 1. Fig. 3 is a plan of the 40 eccentric for moving the sand receptacle, the cover being broken away, on the line 3-3 of Fig. 4. Fig. 4 is a central vertical section of the sand sifter. Fig. 5 is an elevation of a sand sifter when mounted on three legs.

45 Similar reference characters refer to like parts throughout the several views.

The prime requisites of an effective sand sifter for foundries are speed of operation or great capacity, simplicity of construction, 50 and portability. A suitably inclosed electric motor mounted below the screen has proven itself to be the ideal motive power, as a structure thus equipped may be suspended from an overhead track and may 55 travel along just above the sand piles on the molding floor while the workmen shovel in

the sand when standing at both sides of such piles. It is apparent that the sifter should be as low as possible to limit the distance the sand must be lifted, and that power 60 should be supplied to the sifter through the suspending or supporting mechanism.

Sand sifters of this character now on the market lack proper operative connections between the motor and the sieve, and the present invention relates to the mounting of the sieve on the motor support and to the means whereby the screen is moved relative to the motor and its support. The motor is provided with a housing 1 secured to the support 2 in any desired manner, screws 3 preferred, the casing being a ring to which a shell 4 is secured to exclude dust. Two sockets 5 on the casing receive the inner ends of the pipes 6 which connect to the upright 75 pipes 7 by means of the T's 8. A connector 9 at the upper ends of the pipes 7 unites them and receives the suspending ring 10. The line wires 11 and 12 pass through these pipes 6 and 7 to the motor. These pipes 6 80 and 7 constitute the supporting arms for the sifter.

The armature shaft 14 is carried by the housing 1 in proper bearings 15 and 16 and has an eccentric 17 secured to its upper end, 85 and I prefer to secure a fly-wheel 18 to the armature shaft just below the eccentric to absorb the irregularities in the stresses on the shaft. A sieve or other container 19 of any desired character is mounted on the 90 three arms 20, being positioned by the brackets 22 and the screw 23 mounted in one of the brackets. These arms connect to the ring 24, between which and the eccentric 17 is any desired type of bearing 25. A plate 95 26 may be secured to the ring 24 to exclude dust from this bearing and from the eccentric. The supporting frame for the sieve 19 is shown supported by three springs 27, one of which may rest on a saddle 28 secured to 100 one of the pipes 6 while the other two rest on the ends of a bracket 29 mounted on the other pipe 6. A bearing 35 may be placed between the fly-wheel 18 and the top of the motor casing 2, if desired.

105 When the armature shaft rotates, the eccentric imparts a rotary movement to the sieve which is very effective for sifting sand and other granular material. The weight of the motor and its support being 110 much greater than that of the sieve and its contents, the distance through which the

sieve is moved is as much greater than that through which the motor moves. The eccentricity of the member 17 need not be more than one-half inch in order to accomplish the intended purpose and in many cases may be as little as one-fourth inch.

The structure just described is adapted to be supported from overhead tracks so that it can be readily moved to any desired location. In Fig. 5 I have shown a sifter whose motor support 30 has three horizontal bars 31 each connecting to the upper end of a leg 32 whose lower end terminates in a heavy ball or other weight 33. The structure of this device is otherwise the same as that above described.

The proportions and sizes of the several parts of this sifter may all be changed by those skilled in the art without departing from the spirit of my invention as set forth in the following claims.

I claim:—

1. In combination, an electric motor embodying a vertical armature shaft, a support for the motor, an eccentric secured to the upper end of the shaft, a container mounted above the motor and movable relative thereto, yieldable means for supporting the container on the support for the motor, and a ring connected to the container with which the eccentric engages.

2. In combination, an electric motor embodying a vertical armature shaft, a support for the motor embodying tubular arms connected at their upper ends, an eccentric on the upper end of the shaft, a sieve mounted above the motor and movable relative to the motor support, a ring connected to said container into which the eccentric extends, arms extending from the ring to said container, and springs between the motor support and said arms to receive the weight of the container.

3. In combination, a motor support and means to suspend the same, a container above the support and arms between the motor support and the container upon which

the container rests, compression springs mounted between the motor support and said arms to receive the weight of the container and permit gyratory movement thereof relative to the motor support, a motor within said support, and means connecting the motor to the container to impart gyratory movement thereto.

50

4. In combination, an electric motor embodying a vertical armature shaft and an eccentric on the upper end thereof, a support for the motor comprising a casing in which the motor is rigidly secured and suspending arms, a ring above the motor into which the eccentric extends and a bearing for the eccentric within the ring, arms extending radially from the ring, a series of compression springs mounted on the motor support and upon which said arms rest and by which said arms and the ring connecting them are permitted a limited gyratory movement when the eccentric rotates, and a container mounted on said arms.

55

5. In combination, an electric motor embodying a vertical armature shaft, a support for the motor, an eccentric secured to the upper end of the shaft, a sifter mounted above the motor and movable relative thereto, a ring connected to the sifter with which the eccentric engages, and a fly-wheel mounted on said shaft between the eccentric and the motor housing to substantially absorb the irregularities in the stresses on said shaft due to irregular loadings of the sifter and prevent injury to the motor thereby.

70

6. In combination, an electric motor embodying a vertical armature shaft, a support for the motor, an eccentric secured to one end of the shaft, a container mounted adjacent the eccentric end of said shaft and movable relative thereto, yieldable means for transmitting the weight of the container and its load to the support for the motor, and a ring connected to the container with which the eccentric engages.
